UNITED STATES PATENT OFFICE.

CHARLES A. FOSTER, OF BOSTON, MASSACHUSETTS, ASSIGNOR OF ONE-HALF TO HENRY E. WAITE, OF SAME PLACE.

SLEEVE OR CUFF BUTTON.

SPECIFICATION forming part of Letters Patent No. 240,116, dated April 12, 1881.

Application filed August 18, 1880. (No model.)

To all whom it may concern:

Be it known that I, CHARLES A. FOSTER, a citizen of the United States, residing at the city of Boston, in the county of Suffolk and State of Massachusetts, have invented certain new and useful Improvements in Sleeve or Cuff Buttons; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in cuff and sleeve buttons, the principal feature of which is a spring sliding and locking frame or slide for securing the button firmly in the cuff or sleeve, as will be hereinafter more fully described.

In the drawings, Figure 1 is a perspective view of the button; Fig. 2, a side view, showing the button inserted in a cuff; Fig. 3, a plan; Fig. 4, an end view, the sliding frame or slide being in cross-section; Fig. 5, an end view of Fig. 3; Figs. 6 and 7, detailed views of modifications.

A is the head or front of the button, and B the shank, which may be made in one piece, if desired, and of metal, ivory, or other suitable material.

D represents a spring locking slide or frame, made of a single piece of wire passing through two holes in the lower part of the shank (see Fig. 4) and bent into the shape shown in Figs. 1 and 3, the sides being nearer together at the center of its length, and tapering outward therefrom, forming an angle there. One end of this slide D is left open, making a spring of it, and the ends of the wire bent into hooks or stops a a.

C is a perforated groove or recess cut across the shank B, into which the said stops a a fit when the slide is drawn back fully to one side, as shown in Fig. 3, thus preventing the slide from accidentally slipping or being pulled out of the shank B when pulled to one side, as in Fig. 3.

To insert the button into the cuff or sleeve, the spring-slide D is drawn back from the 50 position shown in Fig. 1 to that of Fig. 3, the stops a a lying in the recess C and held therein by the tendency of the slide to spring apart, leaving one side of the shank entirely free or clear. The slide and shank are now passed 55 through the button-holes and the slide moved in the direction of the arrow, Fig. 3, until its bend or angle strikes the shank, the spring of the slide preventing its slipping back again, when the button is securely held or locked in 60 the cuff or sleeve.

To release the button the slide is drawn in the opposite direction, leaving one side of the shank clear, and it may be easily removed from the cuff.

Instead of making the slide D a spring-slide, it may be a closed rectangular wire frame or a flat thin plate of metal, as in Figs. 6 and 7, in which case the shank B is bent at a right angle to one side, forming a shoe, through which 70 the slide works.

I am aware that spring-fasteners formed of bent wire have been heretofore made to pass through the eye of a button to hold the same in place, and that spring locking-plates have 75 also been used in conjunction with the flattened and slotted shanks of buttons. These, however, I do not broadly claim; but,

Having thus described my invention, what I claim as new, and desire to secure by Letters 80 Patent, is—

The combination, in a sleeve-button, of the head A, shank B, having perforated recess C, and the spring locking-slide D, composed of a spring wire frame tapering outward from its 85 center to each end, the free ends of said frame being provided with stops or hooks a a, as specified.

In testimony whereof I affix my signature in presence of two witnesses.

CHAS. A. FOSTER.

Witnesses:

JAS. B. BELL,
JOHN J. KINE.
